UNITED STATES PATENT OFFICE

2,453,995

PORTABLE PNEUMATIC DRILL SUPPORTING
AND HANDLING RIGRobert E. Lee, Bellflower, Calif., assignor to
John Thomas, Norwalk, Calif.

Application June 9, 1945, Serial No. 598,553

2 Claims. (Cl. 77—59)

1

The present invention relates to a novel and improved one-man rig for conveniently and effectively suspending a conventional pneumatic drill, this in a manner to facilitate maneuvering and manipulating the drill and to expedite the drilling of holes in a given plate or sheet of metal.

The principal object of the invention, as the preceding statement of the invention implies, is to provide a practicable and suitably constructed rig characterized by a lever, said lever being adjustably mounted on a relatively stationary support and provided with an adjustable adapter fixture so constructed as to permit the shaft of the drill to be appropriately attached to and suspended therefrom, whereby to permit said drill to be moved about and properly positioned in relation to the work, and then safely and satisfactorily held in the selected position for expeditious and reliable drilling purposes.

Another object of the invention is predicated upon a rig which can be quickly set up for use, transported from place to place and operated by one man, thus permitting the user to drill resultfully more holes than three or four men could do, employing methods and devices now commonly used.

A further object of the invention has to do with a highly adaptable and readily usable rig susceptible of accommodating plates and sheets which are too large to be put under ordinary drill presses and punches.

Having in mind increased production and other attending factors, a rig constructed in accordance with the principles of this invention insures safety to the user and avoids injuries which often occur when the pneumatic drill breaks through a plate and spins, as happens when pursuing present-day drilling practices.

Other objects, features and advantages of the invention will become more readily apparent from the following description and the accompanying illustrative drawings.

In the drawings, wherein like numerals are employed to designate like parts throughout the views:

Figure 1 is a perspective view showing a rig of a one-man type constructed in accordance with the principles of this invention, and illustrating how it is set up for use, how it is associated with the conventional drill, and how the drill is set for drilling operations.

Figure 2 is a vertical sectional view taken approximately on the plane of the line 3—3 of Figure 1, looking in the direction of the arrows.

Reference being had now to the drawings, and

particularly to Figure 1, it will be observed that the work or plate to be drilled is denoted by the reference character A, while the conventional pneumatic drill is denoted by the reference character D.

The lever is denoted by the numeral 5 and comprises an elongated wooden or equivalent bar, which is preferably rectangular in cross-section, and which is formed at its left-hand end with a suitable hand-grip 6. The opposite end thereof is secured to an adjusting and anchoring bracket 7. This bracket is provided with a ring or collar 8 slidably and rotatably surrounding a supporting post 9, said post being provided at its lower end with an appropriate foundation or foot 10 which is fastened (not shown) in any suitable manner to the work or at a point near the work. The bracket 7 is preferably bifurcated, and an end portion of the lever is fastened, as at 11, between the furcations 12. The aforementioned post or standard 9 is provided with upper and lower assembling and retaining collars 13 and 14, these being bolted in place, as at 15. It is sometimes desired, instead of bolting the collars, simply to secure them by set-screws. Either method of fastening the collars 13 and 14 to the post is permissible. But the main idea is to have collars on opposite sides of the adjusting collar 8 of the bracket 7.

An adapter fixture, which serves as a hanger and suspension means, is provided, and this is generally denoted by the numeral 16. It is characterized by a channel-shaped clip 17, this having an appropriate hand-grip 16a at one end. The side flanges embrace and slidably coact with the longitudinal edge portions of the lever, as is obvious. Secured to the intermediate portions of the side flanges (see Fig. 3), as at the points 19, are duplicate depending, suitably shaped hanger limbs 20. A substantially T-shaped fitting 18 is provided, this to accommodate the upstanding shaft or stem on the drill D, said fitting having pins or journals 21 suitably mounted and fastened in the lower end portions of said limb. The numeral 22 designates spacing sleeves interposed between the body portion of the fitting and inner surfaces of said limbs. The upper end of the stem of the drill is threaded to accommodate a nut 23, which has a suitably shaped cap 24 and the underside of the lever rests and rides thereon. Thus, the fixture 16, with its companion parts, constitutes a suitable hanger or bracket for the drill and shiftably mounts said drill on said lever.

The adapter fixture, so called, is such as to permit the drill to be readily moved back and

forth in relation to the lever, this in order to accomplish desired operations with ease and dependability.

As is evident from the drawings, I am concerned primarily with the handle-equipped lever, the adapter device 16 for adjustably saddling and suspending the drill from the lever, and means for adjustably attaching the inner end of the lever to a portable, appropriately supported post or equivalent support, the lever being vertically adjustable and also rotatable in respect to the vertical axis of the post, and the drill being hung from and moved in unison therewith, whereby to promote speedier drilling results and permitting the single user to accomplish as much if not more than three or four men pursuing the usual drilling practices.

It is thought that persons skilled in the art to which the invention relates will be able to obtain a clear understanding of the invention after considering the description in connection with the drawings. Therefore, a more lengthy description is regarded as unnecessary.

Minor changes in the shape, size and arrangement of details coming within the field of invention claimed may be resorted to in actual practice, if desired.

I claim:

1. As a component part of the assemblage of the class described, an elongated channel-shaped clip embodying a horizontal web and vertical side flanges, an upstanding handle attached to and rising from one end portion of said web, said clip being adapted to be shiftably mounted on a horizontal supporting and maneuvering lever, hanger limbs adjustably and detachably connected to and depending from said side flanges, and means for adjustably supporting a conventional drill between the lower ends of said limbs, said means including a horizontal pin and an adjustable nut, 40 said nut having a head adapted to ride and rest against the underside of the lever.

2. In a portable drill rig of the class described, a lever adapted to assume a horizontal position and provided at its outer end with a handle and at its inner end with means for horizontally swingable and vertically adjustable connection with a vertical supporting post, the central body portion of said lever being substantially rectangular in cross-sectional form, an elongated inverted channel-shaped clip aligned and fitted in direct contact with and slideable on the rectangular portion of said lever, a pair of spaced parallel limbs attached to and depending vertically from the side flanges of said clip, a pin mounted horizontally between the lower ends of said limbs, said pin being spaced below, at right angles to said clip and centrally apertured, and a conventional drill having an upstanding stem extending through and upwardly beyond the said aperture between said limbs, the upper end of said stem being provided with an adjusting nut shiftably engageable with the underside of said lever and said clip being provided at one end and on its upper side with an upstanding shifting handle.
